(57) **CLAIM**

The ornamental design for a shirt with protective collar, as shown and described.

DESCRIPTION

FIG. 1 is a perspective view of my new design shown on a person;

FIG. 2 is a top plan view thereof;

FIG. 3 is a front elevational view thereof;

FIG. 4 is a left elevational view thereof;

FIG. 5 is a right elevational view thereof;

FIG. 6 is rear elevational view thereof;

FIG. 7 is an enlarged, fragmentary, front elevational view thereof;

FIG. 8 is a perspective view of a second embodiment of FIG. 1;

FIG. 9 is a top plan view thereof;

FIG. 10 is a front elevational view thereof;

FIG. 11 is a left elevational view thereof;

FIG. 12 is a right elevational view thereof;

FIG. 13 is rear elevational view thereof; and,

FIG. 14 is an enlarged, fragmentary, front elevational view thereof.

The broken line depiction of the human form is for illustrative purposes only and forms no part of the claimed design.

The broken lines shown on the surface of the shirt represent the stitching.
